[57] **CLAIM**

The ornamental design for a golf bag, as shown and described.

DESCRIPTION

FIG. 1 is a front perspective view of a golf bag showing my new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front elevational view, shown in an open position;

FIG. 10 is a rear perspective view shown in a closed position, with the broken line showing of a shoulder belt being for illustrative purposes only and forming no part of the claimed design; and,

FIG. 11 is a rear perspective view thereof, with the bag shown in an open position and the shoulder belt partially detached.
